UNITED STATES PATENT OFFICE.

OSCAR F. LEMCKE, OF CHICAGO, ILLINOIS.

WINDOW SASH.

Application filed December 26, 1925. Serial No. 77,808.

My invention relates to window sashes, and particularly to window sashes for store fronts.

An object of the invention is to provide a simple, practical and advantageous construction of window sash.

Another object of the invention is to arrange an advantageous and effective construction by which the entire area of the window sash may be occupied by glass.

Another object of the invention is to arrange for the effective mounting of the glass and to prevent rattling and breaking of the same.

15 In the accompanying drawings Fig. 1 is a vertical section of a window sash construction embodying my invention, taken on line 1—1 in Fig. 2;

Fig. 2 is a front elevation, with a part 20 of the device broken away for convenience of illustration;

Fig. 3 is a cross section taken on line 3—3 in Fig. 1.

Referring to the drawings I show a flat 25 horizontal sash member 1 and another sash member 2 mounted thereon. A continuous strip 3, preferably made of metal is extended along the members 1 and 2, said strip having an upright portion 3^a fitting 30 against the edge of the member 2 and a horizontal portion 3^b fitting on the top of member 1. This strip is preferably continuous along the length of the window sash. At the upper end of member 3^a and preferably 35 formed integral therewith is a trough-like member 4 serving as a drain for moisture which may run down the glass 5. This trough 4 is provided with apertures 4^a for the escape of moisture. The window glass 40 5 fits against the front of the trough 4 and rests upon a series of supports 6, which are arranged upon the member 3. Each support 6 is preferably made of an upper horizontal portion 7, on which the glass 5 rests, a vertical portion 8 and a lower horizontal portion 9 having an upwardly extending flange 10. Abutments 12—12 are provided, preferably 45 by struck-up portions of the base part 9 of member 6.

50 A certain amount of elasticity or resiliency is provided by the member 7, on which the glass 5 rests. Screws 11—11 are preferably passed through the flanges 10 and into vertically arranged lever members 13 55 which extend through slots 14 in upper horizontal members 6, so that by turning screws

10—10 the lower portions of members 13 may be adjusted to vary the pressure of the upper ends of said members on the glass. To increase that pressure screws 11 are 60 turned so as to draw said members outwardly, that is to the right, referring to Fig. 1, whereby the upper ends of members 13 may be moved inwardly (to the left) and thereby clamp or grasp the glass more firmly. To 65 decrease the pressure on the glass the screws 11 are screwed inwardly, thereby moving the lower ends of members 13 inwardly and their outward ends outwardly, and in a direction away from the glass. Abutments 70 12—12 serve to prevent screws 11 from moving too far in.

A further continuous strip 15 is preferably arranged in front of the glass 5 so as to cover the various operative members referred to, this member 15 preferably having a certain artistic design or figure, such as shown, and preferably having its upper end 16 provided with a downwardly extending flange 17 which may be inserted between member 13 and the glass. Member 13 is preferably provided with apertures or openings through which screws 11 may pass and adapted to accommodate the heads of said screws, as shown in Fig. 1, so that said screws 80 may be turned to effect the desired pressure on the glass while strip 15 is in position.

From the foregoing it will be seen that the glass will be held in firm and tight position so that it will not rattle or work loose, 90 and at the same time it has enough elasticity or cushioning in its mounting to give it a flexible mounting and prevent the glass from being broken or displaced.

It may be understood that changes and 95 modifications may be made without departing from the spirit of the invention.

What I claim is:

1. In a window sash, in combination, a continuous mounting strip having an upper 100 bent portion forming an elastic trough support for the back of the glass, a plurality of bent resilient members forming supports for the glass, said members each having an aperture, means operable through said aperture to vary the pressure of the glass against said trough and a cover member engaging and covering said means and resilient members.

2. In a window sash, in combination, a continuous mounting strip having an upper 110 bent portion forming an elastic abutment for the back of the glass, a plurality of bent

- members each having a resilient upper portion forming a support for the glass and having an aperture therein, levers operable through said apertures in said supports and screws connected to said levers whereby the pressure of the glass against said mounting strip may be varied.
3. The combination in a window sash of a resilient back abutment for the glass, a resilient support for the same, a lever acting on the front of the glass to press it more or less backwardly against the resilient back abutment, said lever being pivoted at said support and means for adjusting said lever.
- 10 4. A sash mounting having a support for the glass formed by a doubled back end portion of a metallic strip having a free end capable of rising and falling to give resiliency, said free end having a slot forming a pivot
- 15 20 for a screw operated lever, whereby the glass is held against an abutment by said lever.
5. The combination of a resilient back, a resilient support and means for holding the glass against the back and on the support,

said means comprising a lever operable 25 through an aperture in said support and a cover member secured to said support by a lever adjusting screw.

6. A window sash construction comprising a continuous strip for mounting on the sash, said strip having an upper bent portion forming a trough and an elastic support for the back of the glass, a series of bent metallic members forming elastic or cushion supports for the glass, screws passing through said members, levers engaged by said screws but such levers passing through slots in said members, and being adapted to operate upon the side of the glass to vary the pressure thereon, and a continuous strip extending 40 along the front of the glass and covering said levers and mounting members and having apertures for the screws.

In witness whereof, I hereunto subscribe my name this 19th day of December, A. D. 45 1925.

OSCAR F. LEMCKE.
